[57] CLAIM

The ornamental design for an enclosure for a trailer brake actuating unit, as shown and described.

DESCRIPTION

FIG. 1 is a front perspective view of the enclosure for a trailer brake actuating unit of the present invention;

FIG. 2 is a side view in elevation of the enclosure for a trailer brake actuating unit of FIG. 1, as seen from the left side of FIG. 1;

FIG. 3 is front view in elevation of the enclosure for a trailer brake actuating unit of FIG. 1;

FIG. 4 is a side view in elevation of the enclosure for a trailer brake actuating unit of FIG. 1, as seen from the right side of FIG. 1;

FIG. 5 is a rear view in elevation of the enclosure for a trailer brake actuating unit of FIG. 1; and,

FIG. 6 is a top plan view of the enclosure for a trailer brake actuating unit of FIG. 1.

The bottom of the enclosure for a trailer brake actuating unit is plain and unornamented.
